A. J. HESS

MOTORMETER LOCK

Filed March 27, 1925

Fig. 1.

Inventor

A. J. Hess

By

Lacy Lacey, Attorney

UNITED STATES PATENT OFFICE.

ALBERT J. HESS, OF SPRINGFIELD, OHIO.

MOTORMETER LOCK.

Application filed March 27, 1925. Serial No. 18,834.

To all whom it may concern:

Be it known that I, ALBERT J. HESS, a citizen of the United States, residing at Springfield, in the county of Clark and State 5 of Ohio, have invented certain new and useful Improvements in Motormeter Locks, of which the following is a specification.

This invention has for its object the provision of means whereby a motormeter will 10 be secured in a radiator cap so that it will be guarded against loss and against surreptitious removal. The invention seeks to provide a simple but efficient mechanism whereby the operation of the motormeter and the 15 placing and displacing of the radiator cap will be premitted but separation of the motormeter from the cap will be prevented except through manipulation by an authorized person. These objects, and other objects 20 which will incidentally appear in the course of the following description, are attained in such a device as is illustrated in the accompanying drawing, and the invention resides in certain novel features which will be particularly pointed out in the appended claims. 25

In the drawing:

Figure 1 is a sectional elevation showing my invention applied to a motormeter;

Fig. 2 is a vertical section on the line 2—2 30 of Fig. 1;

Fig. 3 is a horizontal section on the line 3—3 of Fig. 1, and

Fig. 4 is a horizontal section on the line 4—4 of Fig. 2.

The motormeter 1 is of the usual construction having a stem or hollow body 2 inserted through the cap 3 of the radiator 4. In applying my invention to the motormeter, the nut 5, whereby the motormeter is secured in 40 the radiator cap, is first removed and a yoke 6 is then fitted over the stem or body 2, the nut 5 being then refitted so as to clamp the yoke against the under side of the radiator cap. The yoke 6 is somewhat longer than 45 the stem or body 2 of the motormeter so that it will depend below the same when in place, as shown in Fig. 1, and upon the lower end of the yoke is hung a sleeve 7 having an eye 8 at its upper end to engage upon the yoke, 50 and provided with a longitudinal slot 9 in its lower portion, the lower end of the sleeve being open for a purpose which will presently appear. The sleeve is also provided externally between its ends with an annular 55 recess 10 adapted to receive the tumbler rings 12 which encircle the sleeve and have

an external diameter equal to the maximum external diameter of the sleeve whereby the outer surfaces of the tumblers and the sleeves will lie flush when the parts are assembled, 60 as clearly shown in Figs. 1 and 2. Through the inner circumference of each tumbler ring is formed a longitudinally extending notch 13 which, when the tumblers are properly set, registers with the slot 9 in the sleeve. 65 A locking rod 14 has its upper smooth end fitted within the bore of the sleeve 7, and upon the upper smooth end of this rod are lugs 15 which are adapted to fit within the grooves or spaces defined by the opposed inclined or beveled faces 11 of adjacent tumbler rings, as shown in Fig. 2. These lugs 15 are tapered outwardly to conform to the taper of the faces 11 of the rings and they are also disposed in alignment longitudinally of the locking rod whereby they may pass through the slot 9 in the sleeve when the parts are being assembled, and when the parts are assembled the spaces between adjacent lugs will each receive the inner edge or 70 peripheral apex of one of the rings, as clearly shown in Fig. 2. It will be understood, of course, that the lugs may be connected so as to form a continuous rib having notches 75 in its outer edge.

Upon referring to Fig. 2, it will be noted that the vertical cross sectional outline of a tumbler ring is a truncated triangle presenting a flat inner extremity to bear against the intermediate reduced portion of the 80 sleeve or vertical wall of the recess 10, faces diverging outwardly from said extremity to engage opposite edges of the respective tapered lugs, and basal side faces extending radially outward from the diverging faces 85 to bear against corresponding portions of adjacent rings or the ends of the recess in the sleeve. By this construction, the outer circumferences of the rings and the sleeve 90 will be maintained in flush relation.

The lower portion of the locking rod 14 is threaded, as shown at 16, and is adapted to pass through the upper end of the anchor 17 and the expander 18. The anchor 17 consists of a plurality of arms 19 having their ends outturned, as shown at 20, and connected at their upper ends by a central neck 21 through which the locking rod passes and which is constructed with notches 22 to receive lugs 23 formed on the lower end of the sleeve 7 whereby relative turning of the sleeve or the anchor will be prevented. The 105 110

expander 18 consists of a substantially conical body over which the arms 19 extend and having a projection 24 upon its outer surface to pass between any two of the arms 6 and by its engagement with one of the arms prevent rotation of the expander relative to the arms. The threaded portion of the locking rod 14 passes through and engages the threaded bore of the apex 25 of the expander, as clearly shown in Fig. 2.

Upon the outer surface of the several tumbler rings 12 are displayed in any convenient manner numbers, letters or other characters, indicated at 26, and graduations 15 27 are also formed or displayed upon the rings adjacent the respective characters and in alinement therewith. Similar characters 28 are formed upon the sleeve 7 immediately adjacent the lowest ring 12, as shown in Fig. 20 1. The notch 13 in each tumbler ring 12 is disposed in radial alinement with one of the characters 26 upon the external surface of the ring so that it has a fixed position in the ring and the combination of the lock may 25 be varied by changing the rings, as will be readily understood. In the manufacture of the device, the sleeve is fitted with tumbler rings set to a certain combination of the letters, numerals or other characters displayed 30 upon the outer surfaces of the rings. The anchor and the expander are fitted upon the locking rod with the arms of the anchor close together so that they may be inserted through the filling nipple of the radiator 35 and clear the same. The head 29, which is formed on the locking rod immediately at the upper extremity of the threaded portion thereof, is then turned so that rotation will be imparted to the rod and by its threaded 40 engagement with the expander will cause the expander to ride upwardly inasmuch as rotation of the expander will be prevented by the engagement of the projection 24 against one of the arms. As a result of the 45 movement of the expander upwardly upon the locking rod, the arms 19 of the anchor will be bent outwardly so that their extremities will project beyond the walls of the filling nipple of the radiator and, consequently, any attempt to withdraw the device 50 from the radiator will then be resisted by the engagement of the extremity 20 against the inner surface of the radiator top. The tumbler rings are then set to the combination 55 of the lock in which position the notches 13 in all the rings will be in longitudinal alinement and adapted to register with the lugs 15 upon the rod 14. The sleeve, with the tumbler rings thereon, is then placed 60 over the upper end of the locking rod and pushed home so that the end of the sleeve and the end of the neck 21 will abut. The rings are then shifted so that the notches 65 therein will be carried out of alinement with the respective lugs 15 and the lugs will be

engaged between opposed tapered surfaces of adjacent rings, the device being thus set so that the motormeter cannot be separated from the radiator cap. While I have shown and described the lock as being secured in place by the nut on the motormeter body clamping the suspending yoke to the radiator cap, it will be understood that the yoke may be otherwise secured to the motormeter body, as by riveting or like means. From 70 the foregoing description, taken in connection with the accompanying drawing, it will be seen that I have provided a very simple device which will prevent theft of the motormeter without interfering with the temporary removal of the radiator cap when filling of the radiator is necessary and also permitting the removal of the motormeter for the purpose of repairs if the person making the repairs knows the combination controlling the several tumbler rings. 80

Having thus described the invention, I claim:

1. A motormeter lock comprising a yoke to be secured to the body of the motormeter, 90 a sleeve suspended upon the yoke, an anchoring member including a locking rod engageable within the sleeve, and permutation elements carried by the sleeve and engageable with said locking rod. 95

2. A motormeter lock comprising a suspending member to be secured to the motormeter body, a sleeve carried by said suspending member, an anchor engageable with the lower end of the sleeve and including a plurality of expansible elements, a locking rod engageable within the sleeve, and an expander carried by said locking rod and operable thereby to expand the elements of the anchor. 100

3. A motormeter lock comprising a suspending element to be secured to the body of the motormeter, a sleeve hung upon said element, a locking rod engageable within the sleeve, an anchor fitted to the lower end of the sleeve and including a plurality of expansible arms, a conical expander mounted upon the locking rod within the arms and having an external projection to engage against one of the arms whereby 110 rotation of the locking rod will effect expansion of the anchor arms, and means carried by the sleeve to lock the rod therein. 115

4. A motormeter lock comprising a suspending element to be secured to the motormeter body, a sleeve carried by the said element, a locking rod engageable within the sleeve and provided with a longitudinal series of lugs, an anchoring member carried by the lower portion of the locking rod, and a plurality of tumbler rings mounted upon the sleeve and engageable between the lugs upon the locking rod and provided internally with notches to engage said lugs. 120

5. A motormeter lock comprising a sus- 125

pending element to be secured to the motor-meter body, a sleeve hung on said element and provided with a plurality of external annular grooves and with an internal longitudinal groove, a locking rod engageable within the sleeve and provided with a longitudinal series of spaced lugs adapted to engage the longitudinal internal groove of the sleeve with the spaces between the lugs in
5 the same transverse plane as the external grooves of the sleeves, an anchoring member

carried by the lower portion of the locking rod, and a plurality of tumbler rings having internal annular ribs engaging the annular grooves in the sleeve and between 15 the lugs on the locking rod, said rings each having a radial internal notch to engage the lugs on the locking rod.

In testimony whereof I affix my signature.

ALBERT J. HESS. [L. s.]
